UNITED STATES PATENT OFFICE.

ADELINA W. FORFAR, OF DENVER, COLORADO.

DESIGN FOR AN ERASER-GUARD FOR TYPE-WRITERS.

SPECIFICATION forming part of Design No. 35,294, dated November 19, 1901.

Application filed September 13, 1901. Serial No. 75,357. Term of patent 7 years.

To all whom it may concern:

Be it known that I, ADELINA W. FORFAR, a citizen of the United States, residing at Denver, in the county of Arapahoe and State of Colorado, have invented and produced a new and original Design for Eraser-Guards for Type-Writers, of which the following is a specification, reference being had to the accompanying drawings, forming a part thereof.

10 Figure 1 is a perspective view, Fig. 2 a side or edge view, and Fig. 3 an inverted plan or inner face view, of an eraser-guard, showing my new design.

15 As shown in the drawings, the leading or material features of my design consist of a

thin oblong concavo-convex blade or plate *a* and a handle *b*, joined to the blade at one end and offset therefrom on its convex side.

Having described my invention, what I claim as new, and desire to secure by Letters 20 Patent, is—

The design for an eraser-guard for type-writers, substantially as herein shown and described.

25 In witness whereof I hereto affix my signature in presence of two witnesses.

ADELINA W. FORFAR.
